GEORGE STECK, OF NEW YORK, N. Y.

Letters Patent No. 100,948, dated March 15, 1870.

IMPROVEMENT IN IRON FRAMES FOR UPRIGHT PIANOS.

The Schedule referred to in these Letters Patent and making part of the same

To all whom it may concern:

Be it known that I, GEORGE STECK, of the city, county, and State of New York, have invented an Improved Iron Frame for Upright Piano-Fortes; and I do hereby declare that the following is a full and exact description thereof, reference being had to the accompanying drawings making part of this specification—

Figure I being a front elevation of the frame.

Figure II, a vertical transverse section of the same.

Figure III, a horizontal transverse section thereof.

Figure IV, a rear elevation of the frame.

Like letters designate corresponding parts in all of the figures.

My invention consists in certain improvements in the construction of and attachments to an upright piano-forte iron frame, whereby it is made complete and independent in itself, and may be inserted in the case of the instrument and withdrawn without disturbing any part, and by which the instrument is made much lighter and cheaper, with equal strength and durability.

The frame, having the proper form to receive the strings, is a light skeleton or open frame, and consists of a broad plate, A, at the top, side uprights B B', and bottom C, the top and bottom being connected by oblique brace-ribs D D D, extending in the direction of the strings, and by an oblique counterbrace, E.

Attached to one side and to the bottom C, at one end, is a plate, F, in which the pins of the small strings or wires are inserted. The frame, thus formed, is cast all in one piece.

My improvements are made in connection with this front frame, as follows:

Behind the top plate A of the frame, in a recess therein, so as to bear upon a ledge, s, on the back side of the frame, is secured the wrest-plank G.

Then, upon the back of the wrest-plank are secured the upper ends of a set of metallic braces, H H H, which extend downward across the back side of the frame obliquely in the same direction as and directly behind the brace-ribs D D D of the frame.

The wrest-plank projects back from the frame, so as to separate the braces H H H sufficiently from the frame to give the desired leverage of strength, and to furnish room for the admission of the sounding-board between them and the frame; and in order to hold the braces away at an equal distance from the frame at the bottom, raised bearings or projections z z z are cast upon the back sides of the brace-ribs D D D, to

which the lower ends of the braces are secured by bolts or pins.

These braces hook or clamp around the bottoms of the projecting bearings z z z, as shown at v, Fig. II, and also around the top of the wrest-plank G, as shown at w in the same figure, there being suitable metallic blocks or strips m m m inserted in the wrest-plank for the hooks or heads of the braces to bear on, as represented.

The braces are secured by bolts to the wrest-plank and front frame, as shown. A similar brace, H', may extend down behind the end B' in a vertical direction, as shown in Fig. IV.

A rabbet, n, is cut in the corner of the wrest-plank to receive the edge of the sounding-board for fastening the same in its place between the front frame and the rear braces.

This construction and arrangement of rear clamp-braces, in combination with the front frame, prevent the warping or yielding of the frame to the force of the tuned strings with the lightest possible construction, the braces being so applied as to act most efficiently to strengthen the frame.

The construction is simple and easy; and, altogether, not only is the whole instrument made much lighter thereby, but very materially cheaper than other constructions, with equal strength and durability.

The frame is entirely complete and independent in itself, and it has two lugs, a a, projecting from the sides near the bottom, by which the frame is supported in the case of the instrument, as they simply rest on bearings or blocks therein. Then the top is secured by bolts or screws in the upper part of the case. Thus it is easily secured in place, and can be removed for repairs or other purposes with great facility without disturbing the rest of the instrument.

What I claim as my invention, and desire to secure by Letters Patent, is—

1. The arrangement, in combination, of the iron frame A B C D, the wrest-plank G, and the rear clamp-braces H H, so that the wrest-plank forms the intermediate connection between the frame and the upper ends of the braces, and the sounding-board is admitted between the said frame and braces, substantially as herein specified.

2. The lugs a a on the sides of the frame, for the purpose specified.

Witnesses:

HENRY E. ROEDER,

GEORGE STECK.

JOHN CHRIST.
